CLAIM

The ornamental design for a chair with writing table, as shown and described.

DESCRIPTION

FIG. 1 is a front view of the chair with writing table, showing my new design in folded position;

FIG. 2 is a side view thereof, showing my new design in folded position;

FIG. 3 is a rear view thereof, showing my new design in folded position;

FIG. 4 is a view thereof, taken from above, showing my new design in folded position;

FIG. 5 is a front view thereof, showing my new design in operative position;

FIG. 6 is a side view thereof, showing my new design in operative position;

FIG. 7 is a rear view thereof, showing my new design in operative position; and,

FIG. 8 is a view thereof, taken from above, showing my new design in operative position.

The side not shown is a mirror image of that shown in FIGS. 2 and 6 with the absence of the tablet arm and support thereof.
